TOOL CLEARANCE OVERLAY

Peter H. Kach, Syracuse, N.Y.

(12012 Galena Road, Rockville, Md.)

Filed Jan. 4, 1962, Ser. No. 164,330

4 Claims. (Cl. 33—1)

This invention relates to a device for assisting designers of apparatus requiring the use of tools, such as wrenches and the like for assembly, disassembly and servicing, in providing adequate access for such tools. More particularly the invention relates to transparent overlays having inscribed thereon a tool, such as an end wrench, in positions representing required space for movement for manipulating a fastening such as a screw threaded nut whereby a draftsman may determine accessibility and operability of such tool when applied to such a nut in relation to the surrounding structure of the design.

In particular the invention relates to an overlay in the form of a transparent sheet on which are shown scaled views of a hand or hand holding a tool in a task oriented position, plus manipulation space required, if any, to be used in checking a drawing of a component requiring provision for application of a tool and the manual operation thereof, so that in the drawing stage of design it can be determined whether adequate space allowances have been made.

An object of the invention is to provide the designer of components requiring subsequent manual tasks in the assembly, disassembly and servicing thereof, with a device capable of ready application to a design, while in the design stage, whereby the designer may readily visualize and check the design for space required for application of hand tools in the subsequent assembly of the components, or servicing of the completed structure. The device is preferably based on standard tools used in assembly and servicing, so that the design can be perfected in a manner such that its assembly or servicing may be affected by a standard tool, rendering it unnecessary, as in the servicing field particularly, to provide special tools for the purpose.

More specifically the invention has to do with providing the designer with the means whereby account can be taken of a design in progress in relation to the space required for the application of tools of a standard form in the ultimate assembly or servicing of the component form in the ultimate assembly or servicing of the component subject of the design, whereby the final design, when assembled and erected will have adequate space for access for such tools, as wrenches, which may be required in the assembly or servicing of the apparatus. It is particularly desirable that apparatus be so designed as to be capable of being serviced with standard tools, and that the number of special tools for such servicing be kept to a minimum, or eliminated. Advance consideration, during the design stages, of such problems may be readily had through employment of devices embodying the novel concepts of the present invention. In practice the invention may consist of a set of transparent overlays based on a particular scale, one overlay being provided, for example, for each of a selected range of end wrench sizes of a standard design. Each overlay may have inscribed thereon a wrench shown in two positions to illustrate the necessary wrench movement in tightening or loosening a threaded fastening such as a standard nut to which the wrench is adapted, the wrench being shown as in the normal grasp of an operator's hand to show the overall clearance required for adequate manipulation, of both the wrench and operator's hand.

The above and other novel features of the invention will appear more fully hereinafter from the following detailed description when taken in conjunction with the

2

accompanying drawings. It is expressly understood that the drawings are employed for purposes of illustration only and are not designed as a definition of the limits of the invention, reference being had for this purpose to the appended claims.

In the drawings wherein like reference characters indicate like parts:

FIGURE 1 is a plan view of one transparent overlay, of a set of overlays, adapted for use in connection with a standard nut size and standard wrench as indicated in the legendary material, and for use in checking assembly and component drawings having the scale indicated.

FIGURE 2 is a plan view of a fragmentary portion of the overlay of FIGURE 1 suitably oriented and applied over a drawing of a device having a nut shown in end elevation; and

FIGURE 3 is a plan view of another portion of the overlay of FIGURE 1 suitably oriented and applied over a side elevational drawing of the same device of FIGURE 2, and the side elevation of the same nut.

In FIGURE 1 of the drawings there is shown a transparent sheet of material 20, which may be rectangular, and of Plexiglas, Celluloid or other transparent material of a stable character and non-shrinking. Upon the transparency which may be referred to as an overlay, there is inscribed, in what may be referred to as a plan view, an open end wrench 22 of a standard design, and in which the outline of the jaw faces 24 and 26 are parallel, and the planes thereof disposed at an angle of 15° from the axis 28 of the handle 30. Gripping the handle in a typical manner is a right hand 31, which embraces the end 32 of the wrench. The hand is extended to include a portion of the wrist as at 34, and the grip is between the thumb 36 and forefingers 38 wrapped around the handle. A hexagonal nut 62, shown in outline form is also inscribed, and the center thereof may have a circular hole 18 pierced through the overlay.

Since the more usual wrench applications contemplate hexagonal threaded fastenings, the swing of a wrench, having a 15° angle between the faces 24 and 26 and the handle axis 28 must be not less than 30°, since by turning the wrench over, the 15° angle between the faces 24 and 26 and the handle axis 28 permits the wrench to grip new faces of a hexagonal nut, after rotation of the nut 30°, so that the nut may be advanced in 30 degree increments. Thus to loosen or tighten a nut, there must be provided swing space for the wrench handle through an angle at least as great as 30°, plus an additional angle sufficient to accommodate the wrench operator's hand in closed gripping formation around the wrench handle end, and there should also be provision for any lost motion due to the normal clearance between the jaw faces 24 and 26, and the engaged opposite faces of the hexagonal nut 62.

Upon the overlay there is also inscribed the wrench in a second position with its axis 28', disposed 30° from the first position indicated by the axis 28, the wrench handle being indicated at 30' and the wrench gripping hand being indicated at 31'. It can be seen, that to swing the wrench through 30°, angular space must be provided as is indicated between the lines indicated at 40 and 42, which embrace the outside dimension of the hand in the grip formation outlined in the two positions indicated.

On the overlay there may also be indicated a fragmentary portion of the wrench handle as at 30", with its axis 28" disposed 52½ degrees from the axis 28, such angle being that required for the swing of a wrench having a 15° angle between the faces 24 and 26 and the handle axis 28, when employed in tightening or loosening square headed nuts and fastenings. The angle between line 40, and line 43 serves to indicate the space required by the hand and wrench to rotate a square nut through 52½

degrees. The lines 40, 42 and 43, may if desired, be inscribed upon the overlay. If desired a portion of each of lines 40, 42 and 43 may be a pencil slot as indicated at 39, 41 and 45, so that the designer can readily apply the lines as lines to a drawing.

Upon the overlay may also be inscribed in outline form, the wrench 22 in what may be referred to as a side elevation as at 60, the wrench being shown applied to a hexagonal nut 62, with its axis indicated as at 64. The free end of the wrench is shown embraced by the inscribed outline 66 of the right hand in normal gripping relation thereto, the outline being adapted to show the up and down clearance required for the wrench and the operator's hand for the wrench application shown.

Upon the overlay, as at 70, is shown what may be referred to as an end elevational view, with the inscribed outline 70 of a hand and an inscribed outline 74 of the wrist, the hand grasping the same wrench 22, and at 70' and 70" are shown inscribed the outlines of the hand gripping the wrench displaced as would occur upon moving the active jaw end of the wrench handle through an angle of 30°, or 52½°, respectively about the axis indicated at 76 as would occur in turning the nut 62, through 30° or 52.5°, the latter angle being necessary for a nut having a square head.

In FIGURES 2 and 3 are shown a typical end elevational view, and a sectional view thereof, of a layout drawing, of a device having a pipe line having a hexagonal pipe fitting nut 80 and piping 81 enclosed in a housing having a top wall 82, end wall 83, side walls 84 and 86, and a bottom wall 88. The end wall has been drawn as cut away by the designer as at 90 to provide an access opening to reach the nut 80, and would in practice be provided with a flat removable cover plate, not indicated, which would be applied to close the housing opening.

An application of the overlay outline of FIGURE 1, suitably oriented, is shown in FIGURE 3, to illustrate how the layout designer may quickly determine by use of the side elevational outline of the overlay, the feasibility of the design, when a standard wrench 60 for tightening or loosening the pipe nut 8 is to be accommodated by inserting the wrench through the opening 90. In FIGURE 2, the plan view portion of the overlay has been laid over the end elevation drawn by the designer to indicate whether there is sufficient opening to permit the required 30° of wrench swing, plus the space required by the operator's hand, the total angle being that between lines 40 and 42. In either FIGURE 2 and 3, without recourse to the overlay, it might appear to the designer, that the nut would be sufficiently accessible to a standard wrench through the opening provided at 90. In FIGURE 2 there is a space sufficient for a 30° swing for a standard wrench handle, but not when gripped in a normal manner by the hand of an operator. The designer can at once see that some change should be made in the housing design. By cutting away a portion of the bottom plate as bracketed at 92 and a portion of the side plates as bracketed at 94 and 96, adequate opening space could be provided. All that the designer need do is to provide such an enlarged opening, and provide a closure member that will have opposite side portions, and a bottom portion as well as the end portion to close the aperture.

Thus the designer is able to quickly observe the requirements, and check his design, and provide a design, wherein a wrench of a specified standard form when held by a hand no larger than 95 percentile in size, can easily service the nut shown.

Referring again to FIGURE 3, it can be seen that in order to provide a proper grip upon the wrench there shown, the fingers 38 of the hand must have clearance from the opening edge 87 of the housing bottom 88, and the clearance thus necessitated, places the wrench at an awkward angle in respect to the axis and location of the nut 80 within the housing. By eliminating a portion of the bottom plate as indicated by the bracket 92, the

wrench axis may be swung around so as to extend from the nut at a more favorable angle approaching 90° to the axis of the nut 80.

In FIGURE 2, by removing portions of the side walls, as indicated by the brackets 94 and 96, the portion of the side wall 86 to be removed, being indicated by the broken line 93 in FIGURE 3, it can be seen from the overlay that adequate clearance for the hand and wrench to swing through an angle of 30° is provided. The aperture 18 in the overlay is of sufficient diameter to allow a pencil point or a divider or other pointed object to extend therethrough to act as a centering pin, so that the overlay may be swung angularly over a drawing to determine the best manner in which to provide the necessary clearance in the housing layout design for the application of the necessary tool required for assembly, or service, when the item under design subsequently reaches the erection or production stage.

The uses for the end elevational outlines 70, 70' and 70" of the hand gripped wrench, which quickly show the space requirements for a 30° or 52½° throw of the wrench will readily appear from the foregoing, it being necessary to provide room for the hand that holds the wrench at the beginning of the throw, as well as at the end of the throw, plus additional room the outlines 70 and 70' showing such end positions for a 30° wrench throw, and 70 and 70" showing the end positions for a 52½° wrench throw.

Each of the nuts shown in the overlay of FIGURE 1 are of the same size and as indicated, the overlay will preferably indicate the size of the nut to which it is adapted, the make of wrench such as the fictitious trade name craftool, and the percentile of hand sizes embraced by the hand outlines, which in this case may be selected as 95th percentile, which means that the outlines of the hands shown on the overlay, if having a scale of 1"=1", or full size, will be sufficiently large to accommodate 95% of the hands of the workers who may be expected to engage in erection or servicing of the constructions under design.

The invention when applied to wrenches contemplates a set of overlays for each standard size wrench at scales commonly used such as 1:1, 1:2, 1:4 etc. For example a set of overlays for full scale, that is 1:1 use, will embody hand outlines statisticly scaled at full size at the percentile selected, but will vary in the wrench size outlined. The wrench size illustrated is designated in the legendary matter in the box as a $\frac{1}{16}$ " wrench.

In preparing the overlays with the inscribed wrench in the grasp of an operator, it is essential to employ a hand size sufficiently large so that the vast majority of operators who may be expected to manipulate the particular tool in the space to be provided, will be accommodated. For this purpose it is desirable that the grasping hand inscribed in the overlays be based on a fairly high percentile hand and wrist of anthropometric measurements. Such a hand size may be derived from a particular source such as H. T. E. Hertzberg, D. S. Daniels and E. Churchill in Anthropometry of Flying Personnel, 1950, Technical Report 52-321, Wright Air Development Center, and the source thereof may be indicated upon each overlay together with the percentile used in outlining the wrench gripping hand inscribed on the overlay. In addition the wrench size, the trade name if any, and the scale are indicated, in the box in the lower right corner of FIGURE 1.

It will of course be apparent that the overlays are designed for right hand use. Should it seem desirable to take into consideration the use of a tool held by a left hand, the overlay may be turned over. While the nut, for example in the plan view of the overlay is shown with its flats oriented transversely, it will be understood that the nut, after having been turned 30°, will require the wrench to be inverted. The wrench could be shown in such position also, but by reason of the centering

aperture 18 being in line with the centerline 28 of the tool, such a view is not essential, since the grip on the wrench would vary little when inverted.

The various views may be also used to indicate the space requirements for other tools such as a screwdriver, assuming the handle would have a comparable shape. The grip of a screwdriver handle would not necessarily enlarge the hand outline to any great extent, and overlay may be employed to indicate whether sufficient room has been provided to manipulate such a tool of a standard length.

While only one form of the invention has been illustrated, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. As an article of manufacture, a substantially transparent sheet of material for use over a drawing of a detail of a component of an assembly having a part such as the head end of a threaded fastening requiring the application of a hand tool in the ultimate assembly or servicing of the component, said sheet of material having stiffness, and said sheet of material having inscribed thereon the outline of the head end of a threaded fastening to which a standard tool is to be applied for rotating the fastening, and an outline of a standard tool in engagement therewith in the normal grip of an operator's hand of a selected percentile in plan view whereby the space requirements for said tool and an operator's hand may be quickly checked against the component design for actuation of the threaded fastening thereof, said sheet having narrow linear slots disposed on lines closely embracing the outline of the operator's hand and converging at the center of the head end of the threaded fastening.

2. As an article of manufacture, a substantially transparent sheet of material for use over a drawing of a detail of a component of an assembly having a part such as the wrench head end of a threaded fastening requiring manipulation in the ultimate assembly or servicing of the component by a standard size tool such as a standard wrench of corresponding size to determine space requirement for tool movement, said sheet of material having stiffness, and said sheet of material having inscribed thereon the outline of the wrench head end of a threaded fastening with aperture means to indicate the center thereof, and two outlines in plan view of a standard tool in engagement therewith in the grip of an operator's hand of a selected percentile in two positions designating the range of movement of the tool and hand outline required for manipulation of the fastening whereby the space requirements for said tool in the grip of an operator's hand may be quickly checked against the component design for actuating the threaded fastening thereof.

3. As an article of manufacture, a substantially transparent sheet of material for use over a drawing of a de-

tail of a component of an assembly having a part such as the wrench head end of a threaded fastening requiring manipulation in the ultimate assembly or servicing of the component by a standard size tool such as a standard wrench of corresponding size to determine space requirement for tool movement, said sheet of material having stiffness, and said sheet of material having inscribed thereon the outline of the wrench head end of a threaded fastening in end elevation and aperture means to indicate the center thereof, and a first outline in plan view inscribed thereon of a standard tool in engagement with said fastening in the grip of an operator's hand of a selected percentile, said overlay having inscribed thereon a second outline in plan view of the same tool in the same grip of the said operator's hand angularly disposed about the said center means from said first outline by an angle representing not less than the minimum angular increment of movement of the tool required in the continued loosening or tightening of a threaded fastening member corresponding to the inscribed fastening outline whereby the space requirements for said tool in the grip of an operator's hand may be quickly checked against the component design for actuating the threaded fastening thereof.

4. As an article of manufacture, a substantially transparent sheet of material for use over a drawing of a detail of a component of an assembly having a part such as the polygonal wrench head end of a threaded fastening requiring manipulation in the ultimate assembly or servicing of the component by a standard size tool such as a standard wrench of corresponding size to determine space requirements for tool movement, said sheet of material having stiffness, and said sheet of material having inscribed thereon the outline of the polygonal wrench head end of a threaded fastening in end elevation said sheet having an aperture at the center of the threaded fastening and said sheet having inscribed thereon a first outline in plan view of a standard tool in engagement with the fastening in the grip of an operator's hand of a selected percentile, said overlay having inscribed thereon a second outline in plan view of the same tool in the same grip of the said operator's hand angularly disposed about said aperture from said first outline by an angle representing not less than the minimum angular increment of movement of the tool required in the continued loosening or tightening of a threaded fastening member corresponding to the inscribed fastening outline whereby the space requirements for said tool in the grip of an operator's hand may be quickly checked against the component design for actuating the threaded fastening thereof.
